TAIL GATE LATCH

John George Sand, Galion, Ohio

Application January 23, 1941, Serial No. 375,667

3 Claims. (Cl. 298—23)

The present invention relates to new and useful improvements in tail gate latches for dump trucks and has for its primary object to provide, in a manner as hereinafter set forth, novel means for automatically releasing and securing the tail gate when the body of the vehicle is raised and lowered.

Another very important object of the invention is to provide an automatic tail gate latch of the aforementioned character which is adapted to be expeditiously installed for operation on a conventional dump truck without the necessity of making material structural alterations.

Still another very important object of the invention is to provide an automatic tail gate latch of the character described which may be conveniently rendered inoperative when desired and which will interfere in no way with the usual manually operated tail gate control of the vehicle.

Other objects of the invention are to provide an automatic tail gate latch for dump trucks which will be comparatively simple in construction, strong, durable, highly efficient and reliable in operation, compact and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a dump truck body and frame equipped with a device 35 constructed in accordance with the present invention, showing the body in lowered position.

Figure 2 is a side elevational view thereof, showing the body in raised position, the intermediate portion of said body and the chassis frame being broken away.

Figure 3 is a view in front elevation.

Figure 4 is a perspective view of the invention with certain of the elements omitted.

Figure 5 is a side elevational view, showing the 45 device after it has been rendered inoperative.

Figure 6 is a detail view in vertical section through the automatic overload release clutch.

Figure 7 is a detail view in perspective of a portion of the release clutch.

Referring now to the drawings in detail, it will be seen that the reference numeral 1 designates the usual chassis frame of a dump truck. Pivotally mounted at 2 for swinging movement in a vertical plane on the rear end portion of the

5 chassis frame 1 is a sub-frame 3. Fixed on the sub-frame 3 is an underframe 4 which carries the box or body 5. A tail gate 6 closes the rear end of the body 5, said tail gate being pivotally connected at its upper end, as at 7, to said body.

10 Journaled in the forward portion of the underframe 4 is a transversely extending rocker shaft 8. Fixed on one end portion of the rocker shaft 8 is a hand lever 9. Formed integrally with the end portion of the hand lever 9 which is fixed to the rocker shaft 8 in an arm 10. An arm 11 is fixed on the other end portion of the rocker shaft 8. Links 12 have their forward end portions pivotally connected to the free end portions of the arms 10 and 11. The rear end portions of the links 12 are pivotally connected to the forward ends of longitudinally extending rods 13. The rear ends of the rods 13 are connected to hooks 14 which are slidable on the rear end portion of the frame 4 and which are engageable with a bar 15 for releasably securing the tail gate 6 in closed position.

15 Fixed on the end portion of the rocker shaft 8 which carries the hand lever 9 is a sleeve 16 having a threaded end portion 17. On the other end of the sleeve 16 is a head or disk 18. On the face of the disk 18 which is adjacent the sleeve 16 are beveled clutch teeth 19. Rotatably and slidably mounted on the sleeve 16 is an angular lever 20 having an inwardly curved lower edge 21. It will be observed that the lever 20 is mounted at an intermediate point on the sleeve 16. As best seen in Figure 6 of the drawings, the side of the lever 20 which is adjacent the disk 18 has formed therein substantially V-shaped grooves 22 for the reception of the correspondingly shaped teeth 19. Mounted on the threaded end portion 17 of the sleeve 16 is a nut 23. A coil spring 24 on the sleeve 16 has one end engaged with the nut 23 and its other end engaged with the lever 20 for forcing said lever against the disk 18. It will thus be seen that an overload connection is provided between the lever 20 and the rocker shaft 8. The tension of the coil spring 24 may be regulated as desired by adjusting the nut 23.

20 Mounted on the forward portion of the chassis frame 1 is a metallic plate 25 from which a pin 26 projects. Pivotally mounted on the pin 26 is a hook 27 which is operatively engageable with the lever 20 in a manner to rock the shaft 8 when the dump body 5 is raised. Fixed to the lower portion of the hook 27, as by soldering or welding, is a strengthening plate 28 comprising an apertured, angularly extending upper end portion 29

through which the shank of the hook 27 passes. A spring 30 has one end connected to the plate 28 and its other end connected to an outwardly extending flange 31 on the plate 25 for swinging the hook 27 upwardly to a substantially vertical position when the body 5 is raised, as seen in Figure 2 of the drawings. A stop screw 32 is adjustably mounted in the flange 31 for engagement with the plate 28 for regulating the travel of the hook 27 under the influence of the coil spring 30.

Mounted adjacent the shaft 8 and paralleling same is a comparatively short rocker shaft 33. On the outer end of the shaft 33 is a hand lever 34. Fixed on the inner portion of the shaft 33 is an arm 35. Pivotally connected to the arm 35 is a forwardly and upwardly extending rod 36. On the forward or free end of the rod 36 is a shoe 37 in the form of a metallic plate comprising an upturned forward end portion which is engageable slidably beneath the bottom of the body 5. A spring 38 is connected to the rod 36 for supporting same and the shoe 37 in raised position. The shoe 37 is engageable with an angularly extending upper portion 39 of the hook 27 for disengaging said hook from the lever 20 when desired. A guide 40 is provided for the shoe 37 adjacent the lever 20. It will be noted that the shoe 37 is operable between the forward portion of the lever 20 and the guide 40.

Stops 41 are provided on the underframe 4 for limiting the swinging movement of the hand lever 34 in opposite directions. Adjustably mounted on the sub-frame 3 are stops 42 for limiting the swinging movement of the hook 27 when the dump body 5 is in lowered position.

With the body 5 in lowered position and the tail gate secured by the hooks 14, the hook 27 is engaged over the forward end portion of the lever 20 in the manner shown to advantage in Figures 1 and 4 of the drawings. When the body 5 is raised the hook 27 swings the lever 20 downwardly thereby rocking the shaft 8 in a direction to cause the hook 14 to release the tail gate 6. Of course, the lever 20 passes upwardly out of engagement with the hook 27. With the body 5 in raised position the lever 20 and the hook 27 are in the positions shown in Figure 2 of the drawings. When the body 5 is lowered the hook 27 engages the inwardly curved lower edge 21 of the lever 20. As the body continues to descend the lever 20 is swung forwardly and upwardly while the hook 27 is swung forwardly and downwardly. This continues until the hook 27 clears the forward end of the lever 20 when it is swung upwardly over said lever by the spring 30. The device is now ready for the next operation. The stops 42 definitely limit the swinging movement of the hook 27 in opposite directions when the body 5 is in lowered or substantially lowered position.

When it is desired to render the automatic control inoperative, the shaft 33 is rocked through the medium of the hand lever 34 for forcing the shoe 37 forwardly between the bottom of the body 5 and the portion 39 of the hook 27 substantially in the manner of a wedge. Thus, the hook 27 is forced forwardly and downwardly out of engagement with the lever 20, as seen in Figure 5 of the drawings. In this manner the automatic control is disconnected and the manually operated mechanism may be used for latching and unlatching the tail gate.

Should sufficient stress occur between the lever 20 and the rocker shaft 8 to overcome the ten-

sion of the coil spring 24 said lever 20 will ride over the clutch teeth 19. Thus, the members 8 and 20 will be automatically disconnected in the event of an overload.

It is believed that the many advantages of an automatic tail gate latch constructed in accordance with the present invention will be readily understood and although a preferred embodiment of the device is as illustrated and described, it is to be understood that changes in the details of construction and in the combination and arrangement of parts may be resorted to which will fall within the scope of the invention as claimed.

What is claimed is:

1. The combination with a vehicle including a chassis frame, a dump body pivotally mounted on said frame, a tail gate on said body and means including a rocker shaft for latching said tail gate in closed position, of a lever, an overload clutch releasably connecting said lever to the rocker shaft for actuating said rocker shaft, and a hook pivotally mounted on the chassis frame and engageable with the lever for actuating same for unlatching the tail gate when the body is raised.

2. The combination with a vehicle including a chassis frame, a dump body pivotally mounted on the frame to assume load-carrying position and dumping position, a tail gate pivotally mounted on said body with means on the body including a rocker shaft for releasably securing the tail gate in a closed position, a lever carried by the rocker shaft, an overload clutch connecting said lever to said shaft, said lever including a shouldered face and an arcuately curved face, and a spring influenced hook-shaped member pivotally mounted on the chassis frame to engage with the shouldered face of said lever for imparting rotation to the rocker shaft in one direction to cause

3. The combination with a vehicle including a chassis frame, a dump body pivotally mounted on the frame to assume load-carrying position and dumping position, a tail gate pivotally mounted on said body with means on the body including a rocker shaft for releasably securing the tail gate in a closed position, a lever carried by the rocker shaft, an overload clutch connecting said lever to said shaft, said lever including a shouldered face and an arcuately curved face, a spring influenced hook-shaped member pivotally mounted on the chassis frame to engage with the shouldered face of said lever for imparting rotation to the rocker shaft in one direction to cause said first means to release the tail gate on the movement of the body into dumping position and to engage the arcuately curved face to impart rotation to the rocker shaft in a reverse direction to cause said first means to secure the tail gate in a closed position on the body moving into load-carrying position.

3. The combination with a vehicle including a chassis frame, a dump body pivotally mounted on the frame to assume load-carrying position and dumping position, a tail gate pivotally mounted on said body with means on the body including a rocker shaft for releasably securing the tail gate in a closed position, a lever carried by the rocker shaft, an overload clutch connecting said lever to said shaft, said lever including a shouldered face and an arcuately curved face, a spring influenced hook-shaped member pivotally mounted on the chassis frame to engage with the shouldered face of said lever for imparting rotation to the rocker shaft in one direction to cause said first means to release the tail gate on the movement of the body into dumping position and to engage the arcuately curved face to impart rotation to the rocker shaft in a reverse direction to cause said first means to secure the tail gate in a closed position on the body moving into load-carrying position, a hand operated shoe to engage the hook-shaped member to disengage the latter from said lever, and a manually actuated lever secured to the rocker shaft for the manual rotation of the latter in either direction on the disengagement of the hook-shaped member from the first-named lever.

JOHN GEORGE SAND.
